UNITED STATES PATENT OFFICE.

MORITZ SEGALL, OF SAN FRANCISCO, CALIFORNIA.

METHOD OF PRESERVING FERNS.

1,410,226.

Specification of Letters Patent. Patented Mar. 21, 1922.

No Drawing.

Application filed November 26, 1920. Serial No. 426,508.

To all whom it may concern:

Be it known that I, MORITZ SEGALL, a subject of the King of Rumania, who have declared my intention of becoming a citizen 5 of the United States, residing at San Francisco, in the county of San Francisco and State of California, have invented certain new and useful Improvements in Methods of Preserving Ferns, of which the following 10 is a specification.

My invention is an improved method of preserving ferns, particularly adiantum formosum, (botanical name), commercially known as maidenhair ferns, by means of 15 which method it is possible to preserve ferns in a higher color and more natural state, and more effectively against atmospheric action, than is possible with other known methods.

There are three distinct phases of the process. First, preliminary preparations for 20 bleaching. Second, bleaching. Third, dyeing.

Preliminary preparations for bleaching: The dried ferns are soaked in a bath of 25 caustic soda which has been dissolved in water to a strength of 8 degrees "Baumé scale for heavy liquids." They are left in this bath for three hours, then they are washed of the caustic soda through two or 30 three consecutive baths of cold water, being left from three to four hours in each of these baths.

Bleaching: Chloride of lime is dissolved in water to its essence strength of 13° Baumé 35 scale. It is then left until the heavy part of the mixture settles to the bottom of the tank, when the clearer part (from the top) is extracted and mixed in another vessel with water to a consistency of 3 degrees Baumé 40 scale. To this 3 degree mixture of chloride of lime, add, to every 100 parts, 2 parts of acetic acid glacial 99½%, or, instead of acetic acid glacial may be substituted 1 part commerical hydrochloric acid to every 100

45 parts of the chloride. In this mixture, the ferns which have just been washed from the caustic soda are placed, and in from 20 to 30 minutes (according to the varying texture of some ferns) they are bleached to a 50 pure white and spotless. After being taken out from the bleaching, the ferns are placed in a tank where there is a continuous flow of fresh water, for a period of six to eight hours, until all traces of any chemicals have 55 been washed away.

Dyeing: In the vessel where the dyeing is

to take place, add to three parts of water preferably warm, 1 part glycerine and 1 part denatured alcohol, which gives the liquid a consistency of 8 degrees Baumé scale. This 60 mixture may then be heated a little in order to unite the different ingredients more evenly. (Note that this compound consists of 60% water, 20% denatured alcohol and 20% glycerine C. P.) In a separate vessel 65 dilute the dye in alcohol, and then add this dye essence to the above mixture of glycerine, alcohol and water. (Note that for best results basic dyes must be used). This mixture is then preferably heated to about 70 100 degrees F. The ferns that have gone through the bleaching phase of the process are now dyed in this mixture of dye, glycerine, alcohol and water, being left in the vessel from ten to fifteen minutes. They 75 are then taken out, dried, and are finished, as far as the process has to do with it.

The solution of alcohol, glycerine and dye may be used cold for dyeing as well as hot.

The ferns may also be dyed in dye dissolved in water only, without the glycerine or alcohol mixed therewith; and then placed in a solution of water, glycerine and alcohol or only glycerine and water. Inasmuch as the glycerine and alcohol serve both as a 80 preservative of the fern itself and also as a "setting" of the dye, if the process were carried on in this way, it would mean that this end of the process is divided into two parts,—actual dyeing and preservation. 90

Having described my invention, I claim:

1. The method of preserving ferns which consists in preparing the ferns for bleaching, bleaching the ferns and then dyeing the ferns in a dyeing solution containing glycerine. 95

2. The method of preserving ferns which consists in preparing the ferns for bleaching, bleaching the ferns, and then dyeing the ferns in a dyeing solution containing glycerine and alcohol. 100

3. The method of preserving ferns which consists in preparing the ferns for bleaching, bleaching the ferns, and then dyeing the ferns in a dyeing solution containing equal parts of glycerine and alcohol. 105

4. The method of preserving ferns which consists in preparing the ferns for bleaching, bleaching the ferns, and then dyeing the ferns in a solution containing 60% water, 20% denatured alcohol, 20% glycerine and dye essence. 110

5. The method of preserving ferns which consists in preparing the ferns for bleaching, bleaching the ferns, and then dyeing the ferns in a dyeing solution compounded as follows: add to three parts of warm water, one part of glycerine and one part of denatured alcohol, which gives the liquid a consistency of 8 degrees Baumé scale, heat this mixture a little in order to unite its 10 different ingredients more evenly, dilute the dye in a separate vessel in alcohol, and then add this dye essence to said mixture of glycerine, alcohol and water.
6. The method of preserving ferns which 15 consists in first soaking the dried ferns for three hours in a bath of caustic soda which has been dissolved in water to a strength of 8 degrees "Baumé scale for heavy liquids," washing the caustic soda from the 20 ferns by two or three consecutive baths of cold water from three to four hours in each bath, then bleaching the ferns, and then dyeing the ferns.
7. The method of preserving ferns which 25 consists in preparing the ferns for bleaching, bleaching the prepared ferns in a bleaching solution compounded as follows: dissolve chloride of lime in water to its essence strength of 13 degrees Baumé scale, allow the chloride of lime to 30 stand until the heavy part of the mixture settles to the bottom of the tank, extract the clearer part (from the top) of the chloride of lime and mix it in another vessel with water to a consistency of 3 degrees Baumé 35 scale, and add to every 100 parts of this 3 degree mixture of chloride of lime 2 parts of acetic acid glacial 99½%, and then dyeing the bleached ferns in a dyeing solution containing glycerine and alcohol.
8. The method of preserving ferns which 40 consists in soaking for three hours the dried ferns in a bath of caustic soda which has been dissolved in water to a strength of 8 degrees "Baumé scale for heavy liquids," 45 washing the caustic soda from the ferns by two or three consecutive baths of cold water, leaving the ferns from three to four hours in each of these baths, then bleaching the ferns in a bleaching solution compounded 50 as follows: dissolve chloride of lime in water to its essence strength of 13 degrees
- Baumé scale, allow the chloride of lime to stand until the heavy part of the mixture settles to the bottom of the tank, extract the clearer part (from the top) of the chloride of lime and mix it in another vessel with water to a consistency of 3 degrees Baumé 55 scale, and add to every 100 parts of this 3 degree mixture of chloride of lime, 2 parts of acetic acid glacial 99½%, and then dyeing 60 the bleached ferns in a dyeing solution containing glycerine.
9. The method of preserving ferns which 65 consists in soaking the dried ferns for three hours in a bath of caustic soda which has been dissolved in water to a strength of 8 degrees "Baumé scale for heavy liquids," washing the caustic soda from the ferns by two or three consecutive baths of cold water, leaving the ferns from three to four 70 hours in each of these baths, then bleaching the ferns in a bleaching solution compounded as follows: dissolve chloride of lime in water to its essence strength of 13 degrees Baumé scale, allow the chloride of lime to 75 stand until the heavy part of the mixture settles to the bottom of the tank, extract the clearer part (from the top) of the chloride of lime and mix it in another vessel with water to a consistency of 3 degrees Baumé 80 scale, and add to every 100 parts of this 3 degree mixture of chloride of lime 2 parts of acetic acid glacial 99½%, and then dyeing the bleached ferns in a dyeing solution containing glycerine and alcohol.
10. The method of preserving ferns which 85 consists in placing the bleached ferns in a dyeing solution containing glycerine.
11. The method of preserving ferns which 90 consists in placing the bleached ferns in a dyeing solution containing glycerine and alcohol.
12. The method of preserving ferns which 95 consists in placing the bleached ferns in a dyeing solution containing equal parts of glycerine and alcohol.
13. The method of preserving ferns which 100 consists in placing the bleached ferns in a dyeing solution containing 60% water, 20% glycerine and 20% alcohol.

In testimony whereof I affix my signature.
MORITZ SEGALL.
